SWITCH OPERATOR FOR CHILDREN

John V. Meistrell, Manhattan Beach, Calif.

Application May 7, 1951, Serial No. 224,929

4 Claims. (Cl. 74—503)

1

My invention relates generally to the art of electric switches having an exposed control arm or toggle, and more particularly to a toggle switch operator for children.

A preferred embodiment of the device comprises a remote control mechanism for operating a conventional wall switch from a station spaced below the switch in such a position as to be within reach of a small child so that he may turn on lights or control other electrical appliances for his own use. The device is particularly advantageous for use with light switches, since it is a matter of common knowledge that most small children are afraid of a darkened room. As a result, the parents are called upon to make countless trips to turn on lights so that the child may get up, put on his bed clothes, or the like. While this chore is performed willingly by the majority of parents, it is nevertheless interrupting and tiresome, and it is obviously an advantage if the child can be made self-sufficient in this respect.

I have discovered that even a small child is quite willing and capable of turning on lights or appliances for his own use when he is provided with control means within his reach. In order that the child be capable of using the control device, it must be easily operable through manual actuation, rugged, and foolproof. An overall consideration is the safety of the child, and to this end there must be absolute safeguards against electrical accidents.

It is therefore a major object of my invention to provide a switch operator which enables a small child to operate an electrical switch from a station below the switch and within his reach.

Another object of my invention is to provide a switch operator which is completely safe for use by small children.

It is also an object of my invention to provide a switch operator which is installed as an accessory to any conventional switch and does not interfere with the normal manual operation of the switch lever or toggle.

Another object of my invention is to provide a switch operator which has a remote control mechanism of increased leverage to facilitate operation of the switch by a child having less than adult strength and dexterity.

It is a further object of my invention to provide a switch operator of the kind described which is adapted for convenient and rapid installation on different types of household toggle switches without modification or disassembly of the latter.

Yet another object of my invention is to provide a switch operator which is simple and foolproof to withstand the rugged usage of children, and is adapted for mass production so that it may be sold at a nominal cost.

These and other objects and advantages of my invention will become apparent from the follow-

2

ing detailed description of a preferred form thereof, and from an inspection of the accompanying drawings, in which:

Fig. 1 is a perspective view of a preferred embodiment of my invention shown installed at a conventional toggle switch;

Fig. 2 is a longitudinal medial section through the device taken along line 2—2 of Fig. 1;

Fig. 3 is a transverse section taken along the line 3—3 of Fig. 1; and

Fig. 4 is a perspective view of the remote control linkage mechanism used in the device.

Referring now to the drawings, and particularly to Fig. 1 thereof, an electrical snap switch is indicated as having an outwardly projecting control lever or toggle 10. In household installation a toggle-operated snap switch having a switch box mounted flush with the wall is almost universally used, and the preferred form of my invention will be illustrated in connection with this type of device. As is conventional, the toggle 10 is pivotally mounted for movement from an upper to a lower position and has a snap or spring-resist action which tends to throw internal electrical contacts rapidly into "on" or "off" positions.

The switch proper comprises a generally rectangular switch block 11 which is centrally positioned within a metal switch box 12, as seen fragmentarily in Fig. 2. A carrier or bracket 13 is attached to the front face of the block 11 and is adapted to be secured to the upper and lower edges of switch box 12. Generally, box 12 is rigidly mounted within the wall structure and bracket 13 is attached firmly thereon, but it will be found that in certain installations either box 12 or bracket 13 may be improperly mounted so that switch block 11 is susceptible to forward movement, creating an installation problem as will be discussed later. To complete the assembly a cover plate (not shown) is normally supplied to cover the front opening of switch box 12 and is adapted to be secured in place by fastening means which engage with bracket 13. The control toggle 10 ordinarily projects through such a cover plate and is exposed for manual actuation. As can be understood, the construction thus far described is conventional, and in and of itself forms no part of my invention.

A preferred form of my switch operator is provided with an elongated rectangular housing 15 having its upper end mounted to the switch bracket 13 in place of the conventional cover plate by means of spaced upper and lower screws 16. It is pointed out that screws 16 are those normally serving to secure the cover plate, and thus no modification of the switch means is necessary for the installation of the operator. Housing 15 lies against the wall surface and extends downwardly to support a pivotally mounted lower control handle or toggle 17. Within the housing

15 I provide linking means which connect lower toggle 17 with switch toggle 10, so that switch 11 may be manually actuated from either toggle. By the use of toggle 17, a small child may operate the lights or other electrical appliances controlled through switch 11 and at the same time, toggle 10 is available for adult use in controlling the switch.

Housing 15 is formed with an upper rectangular plate 20 which is spaced forwardly from the wall surface by rearwardly turned side and top flanges 21. An elongated aperture 22 is cut into the center of plate 20 for accommodating toggle 10 and permitting its normal pivotal movement. In order to accommodate linking means for connecting handle or toggle 17 with toggle 10, it is necessary that edge flanges 21 be made somewhat deeper than those found on conventional switch plates, and for this reason the entire length of toggle 10 does not project through plate 20 as in a normal installation. It is therefore desirable that the thickness of plate 20 be reduced as much as possible around aperture 22 as by means of a shallow dished portion 23.

Depending from plate 20 is an elongated central channel section 25 having a central wall 26 supported by rearwardly turned edge flanges 27. As is best seen in Fig. 2, section 25 provides an inner channel 28 which is opened at the top to the space behind plate 20 and extends downwardly a substantial distance. Connected to the lower end of section 25 is a station box formed by a circular edge flange 30 and a flat front disk or plate 31. Lower toggle 17 is pivotally supported by plate 31 and projects outwardly therefrom through a central aperture 32. Behind front plate 31 is a lower operating space 33 which opens upwardly into channel 28.

In this form of the device, I prefer to decorate station plate 31 with a clown's or animal's face which will be attractive to children. The toggle or handle 17 forms the tongue of the clown's face, and the operation of the device by the movement of the clown's tongue is pleasing and amusing to the child. For small children, the association of a pictorial representation with a desired functional result is an advantageous teaching aid, enabling the child to more quickly understand the operation of the device. At the same time, the housing is ornamental and attractive for sale purposes. Under conditions in which the device is to be used in a room other than a child's room, it may be preferable to eliminate any decoration on the plate 31 to provide a more inconspicuous structure. In any event, the entire housing 15 is preferably formed by an extrusion process from one of a variety of plastic materials such as poly-methyl-methacrylate, poly-vinyl-chloride, the resins of phenol or urea, or the like. By the use of a colored plastic material, I obviate the necessity of painting the device, and provide a durable finish. More important, however, is the fact that the housing 15 is formed of a nonconducting material which effectively insulates lower toggle 17 from an electrical current passing through switch 11.

To support toggle 17, a pair of ears 36 are extended rearwardly from front plate 31 on either side of apertures 32, as is best seen in Fig. 3. The rear portion of toggle 17 is made of increased thickness and bored to serve as a bearing 37 which is rotatably mounted on a transverse pivot pin 38 having its ends journaled in ears 36. At the rear end of the toggle 17 a short crank arm 40 is formed as a longitudinal extension of re-

duced width, extending rearwardly beyond the pivot pin 38. As is best seen in Fig. 2, the length of the moment arm of toggle 17 with respect to the pivot axis 38 is substantially greater than that of crank arm 40 to provide increased leverage and facilitate operation of the device by a small child.

Connected between switch toggle 10 and lower crank arm 40 is a linking means comprising a connecting bar or flat link 42 which is free for vertical movement within channel 28 and has its lower end formed as a yoke 43. Arm 40 is adapted to fit within yoke 43 and is rotatably connected thereon by a crank pin 44. As is seen in Fig. 2, movement of toggle 17 from a lower to an upper position causes arm 40 to move downwardly and effects a downwardly directed vertical movement of link 42. The upper end of link 42 is formed as a cross-head provided with a slot or rectangular opening 46 which fits around the inner portion of switch toggle 10 with only a slight amount of clearance. Vertical movement of link 42 thus causes toggle 10 to be moved pivotally with respect to switch 11 for controlling the electrical contacts therein. Because of the increased leverage or mechanical advantage provided at toggle 17, only a slight manual force need be exerted thereon to throw toggle 10 from its upper to lower position, or vice versa.

Below the opening 46, I provide an elongated guide slot 47 which is adapted to receive the lower fastening screw 16 therethrough for limiting link 42 to substantially vertical movement. At the top of link 42, I provide a stop notch 48 which engages an enlarged rectangular boss 51 extended rearwardly from plate 20 around the upper fastening screw 16 so as to limit the upward travel of the link. A similar enlarged boss 52 may extend rearwardly from plate 20 around lower fastening screw 16 and both bosses bear against the switch carrier bracket 13.

The purpose of bosses 51 and 52 is to act as spacers preventing bracket 13 from being drawn too far outwardly when the screws 16 are tightened. As was previously mentioned, it is sometimes found that the bracket 13 or switch box 12 is not rigidly mounted in the wall structure, and under these conditions it is possible to inadvertently tighten screws 16 to such an extent as to cause bracket 13 to bear frictionally against link 42 and interfere with the operation of the device. The provision of spacing bosses 51 and 52 prevents overtightening and thus enables the device to be rapidly and easily installed by even an inexperienced person.

In the preferred form of the device, toggle 17 and link 42 are formed as a plastic material similar to that used for housing 15. Such a material is an effective electrical insulator, and it can be seen that by making the entire assembly from plastic I eliminate the possibility of an electrical current reaching the child when he operates toggle 17. The use of a plastic material also lends itself to an economical extrusion process permitting the device to be mass-produced and sold at a nominal cost.

While I have shown and described a preferred embodiment of my invention which has been illustrated in connection with a specific type of switch construction, it is apparent that the invention may be modified for use on other conventional switches. Therefore, I do not wish to be limited to the details described herein, except as defined in the appended claims.

I claim:

1. A switch operator for local and remote operation and adapted for mounting as an accessory to an electrical switch having an exposed control toggle pivotally movable between switch operating positions, said operator comprising: a housing formed with fastening holes adapted to receive screws for connection to said switch in place of a cover plate and having an elongated lower portion extending downwardly therefrom, said housing having an aperture therein to expose said control toggle for local manual actuation and said housing edge portion bearing rigidly against a supporting wall surface and defining a rear passageway extending longitudinally therethrough; a control handle pivotally mounted to the lower end of said housing in such a position as to provide a mechanical advantage at the working end thereof for movement by a child between operating positions; and a linking member extending along said passageway and pivotally connected at the lower end to said operating handle, the upper end of said member being slotted and engaged with said control toggle for moving the latter in response to movement of said control handle.

2. A switch operator for local and remote operation and adapted for mounting as an accessory to an electrical switch having an exposed control toggle pivotally movable between upper and lower switch operating positions, said operator comprising: a housing formed for connection to said switch and having an elongated lower portion extending downwardly therefrom, said housing having an aperture therein to expose said control toggle for local manual actuation and said housing having edge portions bearing rigidly against a supporting wall surface and defining a rear passageway extending longitudinally therethrough; bearing means at the lower end of said housing adjacent a lower aperture therein; a control handle pivotally supported by said bearing means and extending through said lower aperture for limited vertical movement, said handle having a relatively short rear crank arm extending rearwardly of the pivot axis whereby to facilitate movement of said handle by a small child; and a linking member mounted for vertical movement in said passageway and rotatably connected at the lower end to said crank arm, the upper end of said member being slotted and engaged with said control toggle for moving the latter in response to movement of said control handle.

3. A switch operator for local and remote operation and adapted for mounting as an accessory to an electrical switch having an exposed control toggle pivotally movable between upper and lower switch operating positions, said operator comprising: a housing formed with fastening holes adapted to receive screws for connection to said switch in place of a cover plate, and having an elongated portion extending downwardly therefrom, the upper portion of said housing being shaped as a cover plate spaced outwardly from said switch by edge flanges and having a central aperture therein to expose said control toggle for local manual operation, said elongated portion having edge flanges bearing rigidly against a supporting wall surface and defining a rear passageway extending longitudinally therethrough; a lower station plate joined to said elongated portion and spaced outwardly by edge flanges, said plate having a central aperture therein; bearing supports extending rearwardly from said station plate adjacent said

central aperture; a control lever pivotally connected to said bearing supports and extending through said aperture for limited vertical movement, said lever having a relatively short rear crank arm extending rearwardly of the pivot axis whereby to facilitate movement of said lever by a small child; and a linking member mounted for vertical movement in said passageway and rotatably connected at the lower end to said crank arm, the upper end of said member being slotted and engaged with said control toggle for moving the latter in response to movement of said control handle.

4. A switch operator for local and remote operation and adapted for mounting as an accessory to an electrical switch having an exposed control toggle pivotally movable between upper and lower switch operating positions, said operator comprising: a housing formed with fastening holes adapted to receive screws for connection to said switch in place of a cover plate, and having an elongated portion extending downwardly therefrom, the upper portion of said housing being shaped as a cover plate spaced outwardly from said switch by edge flanges and having a central aperture therein to expose said control toggle for local manual operation, said elongated portion having edge flanges bearing rigidly against a supporting wall surface and defining a rear passageway extending longitudinally therethrough; spacer bosses extended rearwardly from said cover plate adjacent said fastening holes for engagement with said switch to limit the take-up of the fastening screws; a lower station plate joined to said elongated portion and spaced outwardly by edge flanges, said plate having a central aperture therein; bearing supports extending rearwardly from said station plate adjacent said central aperture; a control lever pivotally connected to said bearing supports and extending through said aperture for limited vertical movement, said lever having a relatively short rear crank arm extending rearwardly of the pivot axis whereby to facilitate movement of said lever by a small child; and a linking member mounted for vertical movement in said passageway and rotatably connected at the lower end to said crank arm, the upper end of said member being slotted and engaged with said control toggle for moving the latter in response to movement of said control handle, said operator being further characterized by the use of a nonconducting plastic material for all of said aforementioned elements whereby said switch is effectively insulated from said control lever.

JOHN V. MEISTRELL.
